8 Claims. (Cl. 155—48)

This invention relates to an article of furniture for use as a chair or bed, the term "chair" being here employed as covering a settee. The article is broadly of that kind in which an extension section is normally supported on a main frame to which said section is hingedly or pivotally connected, the extension section being swung over to extend the supporting surface of the article to convert the chair into a bed.

10 The main object of the present invention is to provide an article of furniture which has a normal chair or bed appearance, according to the use to which it is put, so that the appearance of the article does not immediately betray the fact 15 of its convertibility from a chair to a bed, and vice versa.

A further feature of the invention is to provide a convertible article of furniture which has a comfortable seat height when used, as it normally would be, as a chair, and with a bed surface of usual bedstead height. Hitherto in bed-chairs the provision for a comfortable seat height has generally been accomplished by a bed surface rather lower than that of the average bedstead, 25 or alternatively, if provision has been made for a bed surface of usual bedstead height the seating surface of the article when in chair form has been uncomfortably high. The desired end is achieved according to this invention by elevating 30 a bedding support in that part of the chair which remains resting on the floor until it is in horizontal alignment with another bedding support carried by that part of the chair which is swung over to form an extension.

35 Another feature of the present invention is the construction and arrangement of parts whereby an initial swing over movement of the extension section takes place before the means for elevating the bedding support of the main frame come into operation. The provision made obviates the need for any great effort in the initial movement of swinging over the extension, the greater effort required for effecting elevation of the bedding support of the main frame being then entirely provided by the weight of the extension as it swings down toward the floor.

The invention may be summarised as providing an article of furniture for use as a chair or bed, including a chair base comprising a main frame having side members adapted to be supported on the floor, a movable bedding support extending between the side members, elevating means for the bedding support, an extension section hinged to the main frame, normally constit-

tuting a seat unit and carrying a second bedding support which is adapted to align with the elevated bedding support of the main frame, and means for operating the elevating means of the bedding support of the main frame as said extension is swung over. Preferably the main frame and the extension section are interconnected by hinge bars which are operatively connected to the elevating means of the bedding support, so that such elevating movement is effected automatically as the extension section is swung over. In order to provide for a delay in the elevation of the bedding support of the main frame until after a predetermined initial swing of the extension, said extension is conveniently hinged to the hinge bars above the point of pivotal connection of said hinge bars to the main frame, the axis of pivoting of the extension section being automatically transferred after a predetermined initial swinging movement from the extension section pivots to the main frame pivots.

The accompanying drawings illustrate a practical embodiment of the invention, and in these drawings—

Figure 1 is a pictorial view of the closed-up chair, on a small scale, Figures 2 and 3 are cross sections on lines II—II and III—III respectively of Figure 1, and Figure 4 is a fragmentary transverse section on line IV—IV of Figure 3. Figure 5 is a pictorial view of the chair extended into bed form, shown on a small scale and Figures 6 and 7 are a cross section of line VI—VI, and a half plan looking in the direction of arrow VII, Figure 5. Figure 8 is a fragmentary view similar to Figure 3, but on an enlarged scale, Figure 9 is a fragmentary transverse section on line IX—IX of Figure 8, and Figure 10 is a view similar to Figure 8, but showing the chair in the course of being extended. Figure 11 is a detail view showing the bolster pad and its operating means in more detail, and Figures 12 and 13 are fragmentary elevation and sectional views of the means for latching the chair back to the headboard of the main frame.

In the embodiment illustrated, the main frame of the chair is designated generally by reference A, rests upon the floor on castors 1 and comprises a front board 2, a pair of side boxes 3, a yielding bedding support 4 consisting of an angle-iron frame 5 filled in by a wire-mesh mattress and supporting a flock or other padded mattress 6 which extends between the side boxes 3, and an upright backboard 7, which forms the headboard of the bed when the chair is extended. The mat-

tress 6 is normally housed within the lower part of the well of the main frame A. Other parts of the main frame A are referred to later.

The extension section is generally designated by reference B and comprises a pair of upholstered arms 8, an upholstered back 9 which is pivotally mounted between said arms 8, and a yielding bedding support 10 consisting of an angle-iron frame 11 filled in by a wire-mesh mattress and supporting on its upper side an upholstered seat cushion 12 and on its lower side a flock or other padded mattress 13. The frame 11 extends transversely between a pair of closed-in boxes 14 which extend above the level of the mattress and are partially enclosed within the upholstered arms 8 of extension B. The padded mattress 13 normally depends into the well of the main frame A, and loose bed coverings (sheets, blankets, etc.) are accommodated in the space between the top of the flock or padded mattress 6 of the main frame A and the flock or padded mattress 13 of extension B.

The main frame A and extension B are connected together at their front ends by means of a pair of hinge bars 15, one at each side of the chair, said bars 15 being hinged to the boxes 3 of the main frame A by means of pivots 16 and also to the boxes 14 of the extension B by means of pivots 17. To the lower end of each hinge bar 15 there is pivotally connected the front end of a rearwardly extending link 18 which by its rear end is pivotally mounted on a pin 19 slidably within a horizontally disposed slot 20 provided in the upstanding flange of the angle-iron frame 5. The head of this pin 19 is secured to the apex end of a rocker plate 21 of isosceles triangular shape which is situated near the front end of the main frame A. The pin 19 is pivotally mounted by means of a pivot pin 22 at one of the base corners of the triangular rocker plate 21 to the corner of an inverted L bracket provided in the box 3. The pin 19 is also slidably received within an arcuate slot 23 formed in the wall of the box 3 and has a curvature whose centre is at the pivot 22 of the rocker plate 21, the upper end of the arcuate slot extending beyond the lower end and terminating in substantially vertical alignment with said pivot 22. The pin 19 is normally engaged in the lower end of the arcuate slot 23 and approximately midway along the length of the slot 20 in the frame 5.

At a suitable distance from the backboard 7 of the main frame A there is pivotally mounted another rocker plate 24 of similar shape to rocker plate 21, with its corresponding base corner connected by a pivot 25 to a bracket in the box 3 and its other base corner pivotally connected by means of a horizontally disposed link 26 to the corresponding base corner of the front rocker plate 21. At the apex end of the rocker plate 24 there is provided also a pin 27 which is slidable in another horizontal slot 28 in the frame 5 and also slidable in another arcuate slot 29 identical to slot 23.

With a view to dispensing with a bolster, a bolster pad 30 of flock or other padding or filling material is situated at the head end of the mattress 6 and is adapted to be tilted automatically to an inclined position as the chair is opened. This inclining movement is effected by pivotally mounting a cranked lever 31 on a bracket 32 provided on the frame 5 and connecting the outer ends of its two arms respectively to the rigid frame 33 of the pad 30 and to a slotted bar 34 which is slidable longitudinally relative to the

side of the frame 5. The pad 30 is normally urged into the lowered position by a tension spring 35 acting through the crank 31. The pin 27 of the rocker plate 24 which engages the slots 28, 29 as already described also engages with the slot 36 of bar 34 and when the frame 5 is elevated (see Figure 11) the pressure of the pin 27 against the end of slot 36 also assists in maintaining the pad 30 in the inclined position. During the collapsing of the bed into chair form, that is, as the frame 5 is being lowered into the well of the main frame A, the pin 27 presses against the other end of slot 36 and forces bar 34 rearwardly, thereby swinging the crank 31 on its pivot under the pad 30 which it draws down into the normal position, that is, flush with the mattress 6. The front edge or side of the pad 30 pivots about its top edge, so that this edge may be flexibly joined to the top rear edge of mattress 6.

The extension B is provided with a board 38 which is normally accommodated in the rear part of the well of the main frame A and is adapted to form a foot-end board for the extended bed. The portion of the board 38 which extends above the bedding frame 11 is inclined inwards so that it does not foul the headboard 7 as the extension B is swung over. Fixed legs 39 for supporting the outer end of the extension B are also provided, and these are normally housed in a hollow 40 formed in the back of the upholstered pivoted chair back 9. The chair back 9 has a closure plate 41 which covers the upper part of the hollow 40 and extends down to meet the top of the headboard 7 of main frame A. The chair back 9 is held against swinging movement when in chair form by means of a latch 42 centrally pivoted at about the centre of its length to the inside of the plate 41, in such a manner that the bevelled point 43 of the latch engages a slot 44 in a striking plate 45 carried by the headboard 7. The latch 42 is normally urged into the latched position by a leaf spring 46 and may be disengaged from the striking plate 45 by pressure applied to its upper end through a finger slot 47 in plate 41.

To the upper end of each hinge bar 15 there is pivotally connected the front end of a long link 48 which in turn is pivotally connected to one end of a shorter link 49. The other end of link 49 is secured to the projecting end of a rod 50 which passes transversely through the upholstered back 9, the rod end extending through a bearing block 52 provided within the upholstered arm 8. A tension spring 53 anchored within the box 14 is connected to the short link 49.

Associated with each hinge bar 15 is a locking bar 54 which lies alongside of the hinge bar and has slots therein to permit it to slide longitudinally along the hinge bar 15 without interference by the hinge bar pivots 16, 17. Straps 55 are provided at opposite ends of the bar 54 to embrace the hinge bar 15, a pin 56 provided on the strap 55 nearer the pivot 16 engaging within a curved slot 57 provided in a bracket 58 fixed within the box 3. During the extending of the chair into bed form the movement of the pin 56 along the fixed slot 57 slides the locking bar 54 longitudinally until its outer end engages within a yoke or socket 59 (Figs. 8 and 10) provided in the box 14.

When the sections A and B are superimposed as shown in Figure 3, it will, of course, be understood that the locking bars 54 carried by the hinge bars 15 are in their inoperative positions due to the fact that the pin 56 carried by each

locking bar is disposed in the bottom end of the slot 57 of its related bracket 58. As the section B is tilted forwardly on the pivots 17, the hinge bars 15 and the locking bars 54 do not move until after the said section B moves counter-clockwise beyond the dotted line position of B shown in Figure 3. When the abutments 66 on the floors of the boxes 14 contact with the hinge bars 15, the latter begin to turn about the lower pivots 16. Since the locking bars 54 are carried by the hinge bars 15, it will, of course, be apparent that the pins 56 of the locking bars will ride in the slots 57 of the brackets 58 and as the hinge bars 15 continue their forward movement, the locking bars 54 will be pushed forwardly until, when the section B reaches its ultimate forward limit, the front ends 54^a of the locking bars are moved into locking engagement with the so-called yokes 59 carried by the section B. When the ends 54^a of the locking bars are engaged with the yokes 59, the pin 56 of each locking bar engages the upper end of its related slot 57 in one of the brackets 58. Since the brackets 58 are carried by the section A and the yokes 59 are carried by the section B, the effect of the locking bars 54 engaging 25 58 and 59 will be to brace the section A relative to section B across the joint between them. In other words, when the bars 54 are shifted forwardly by the tilting forward of the section B, said bars 54 in effect brace the section B relative to section A, because in addition to the pivots 16 and 17, the hinge bars 15 have the benefit of the supplemental points of support afforded by the engagement of the pins 56 with the upper 35 ends of the slots 57 as well as the interlocking of the front ends 54^a of the bars 54 with the yokes 59. This bracing is desirable so that there will be no looseness at the joint between the sections A and B when the device is occupied as a bed. 40 Ordinarily, the mid-section of a bed assumes the heaviest weight, at least initially when being occupied, and the effect of the locking bars is to guard against the weight of a heavy person imposing his weight at the mid-section of the bed 45 and obtaining the effect of having the head and foot boards tend to lift upwardly.

Assuming that the device is in use as a bed as shown in Figure 6 and it is desired to convert it back into the form of a chair, the section B is elevated and due to the fact that the ends 54 of the locking bars are still engaged initially with the yokes 59, no movement will take place about the pivots 17 but on the contrary, such pivoting movement will be fully transferred to the pivots 16. Since the locking bars 54 are freely slideable on the hinge bars 15, and the hinge bars move in response to upward tilting of the section B, the pins 56 on the bars 54 will begin to move in the slots 57. Continued tilting of the section B toward the section A causes additional travel of the pins 56 in the slots 57 so that when the section B moving clockwise approximately reaches the dotted line position in Figure 3, the ends 54^a of the locking bars 54 will be withdrawn from the yokes 59. As will be observed from the drawings, the radius between the pivots 16 and the pins 56, when the sections A and B are in superimposed relation, is greater than the radius between the pivots 16 and the upper end of the slots 57, and the said slots 57 are so designed as to propel the locking bars 54 forwardly to locking position in relation to the yokes 59 when the sections A and B are opened to form a bed, and, 75 on the other hand, withdraw the locking bars

from the yokes 59 when the parts are moved to form a chair.

A coil spring 60 (Fig. 8) is coiled around the pivot 16 which assists in raising the extension section B as it is swung up from the floor. That is to say, one end of the spring 60 is anchored to the hinge bar 15 while the other end engages beneath the top of the box 3 so that as the extension section B tilts forwardly, as shown in Fig. 10, the spring becomes wound or tensioned. Thus, when the section B is lifted from the floor, the energy stored in the spring will assist in lifting the weight of the section B.

The seat cushion 12 is constructed as a separate unit so as to be movable relative to the frame 11, the front end of the cushion being resiliently supported from the inner walls of the boxes 14 by suspension springs 61 and at the rear end upon spring-poised bolts 62 supported by frame 11.

The openings 63 in the boxes 3 and 14 which allow of free movement of the hinge bars 15 are normally covered by a flexible strip 64 of suitable upholstery material, the said strip 64 allowing the seat cushion 12 to sink freely under load, a gap 65 being provided above the front board 2 for the same purpose.

It will be understood that the mechanism within the boxes 3 and 14 and the bolster pad operating means is duplicated for both sides of the chair so as to provide uniform movement of all working parts.

When the chair is to be extended into bed form the extension B is released from frame A by unlatching the chair back 9 and then swinging over the extension B by hand. During its initial swing-over movement the extension B swings about the upper pivots 17 and does not impart motion to the hinge bars 15 until it reaches the position shown in dotted lines in Figure 3. The initial swing-over movement of the extension B is accompanied by the swinging over relative to said extension of the pivoted chair back 9, owing to the different locations of the pivotal points of the extension B (about pivots 17) and the links 48 (about the upper ends of the hinge bars 15), the links 48 causing links 49 to swing around the pivots 50 and thus effecting the swing over of the back 9. The legs 39 are now uncovered so as to be free to contact with the floor when the extension is fully swung over. When the extension B reaches the position shown in dotted lines in Figure 3, abutments 66 on the floors of the boxes 14 contact with the hinge bars 15, so that thereafter the hinge bars 15 and the extension B swing down together, the point or axis of pivoting of the extension B being automatically transferred from pivots 17 to pivots 16. As soon as the hinge bars 15 begin to move they impart swinging movement to the rocker plates 21, 24 and their respective pins 19, 27 moving in unison through the slots 23, 29 elevate, without tilting, the frame 5 with mattress 6 and pad 30, until the mattress becomes co-planar with mattress 13. Simultaneously with their traverse through the arcuate slots 23, 29 the pins 19, 27 move along their respective horizontal slots 20, 28 in the frame 5, but since the upper ends of the arcuate slots 23, 29 extend forwardly beyond the lower ends thereof, and also beyond the forward ends of slots 20, 28, the pins 19, 27 by pressing upon the forward ends of said slots 20, 28 carry the frame 5 forward so that the front end of mattress 6 is brought into contact or close to the rear end of mattress 13 of the extension B. The 75

action of inclining the bolster pad 30 and of operating the locking bars 54 have already been described. The elevated frame 5 is held steady by the entering of the pins 19, 27 into the slightly hooked forward ends 66 of slots 20, 28 in frame 5.

When collapsing the bed into chair form the operation is in general the reverse of that of extending the chair, that is, the frame 5 with the mattress 6 and bolster 30 is lowered within the well of the main frame A during the initial swinging movement of the extension B. The slightly hooked ends 67 of slots 20, 28 suffice to hold the pins 19, 27 temporarily while the frame 5 is carried rearwardly for a certain distance. The locking bars 54 also assist to this end as they ensure that the hinge bars 15 move positively with the extension B during its initial swinging movement, the hinge bars 15 moving about pivots 16. The hinge bars 15 through the pins 56 and curved slots 57 eventually disengage the locking bars 54 from their yokes or sockets 59, and then contact with the front walls of boxes 3, thereby arresting their swing. The extension B now pivots about pivots 17 on the hinge bars 15, and the links 48, 49 function to swing over the chair back 9 into its normal position.

We claim:

1. An article of furniture for use as a chair or bed, comprising, a main frame including side boxes adapted to be supported on the floor, said boxes provided with arcuate slots in their inner walls, a bedding support extending between said side boxes and including frame bars provided with horizontal slots, pins slidable in the arcuate slots of the boxes and in the horizontal slots of the frame bars, an extension section normally constituting a seat, hinge means for connecting the extension section to the side boxes, said extension section carrying a second bedding support on its underside, and means connected to said pins and operatively connected to said hinge means for actuating the pins in said slots to first elevate and then slide the bedding support of the main frame when said extension section is swung over on the hinge means to bring said bedding supports together in horizontal alinement.

2. An article of furniture for use as a chair or bed, comprising, a main frame including opposite side members adapted to rest on the floor, a bedding support extending transversely between said side members, cooperating means associated with the bedding support and the side members for mounting the bedding support to move vertically and then horizontally with respect to the side members, an extension member normally constituting a seat and having a bedding support at its underside, hinge means connecting the front end of the extension member to the side members of the main frame, means actuated by said hinge means and operatively connected with the bedding support of the main frame to first elevate the bedding support as the hinge means is actuated by the tilting movement of the extension member and then to slide the bedding support forwardly toward the bedding support of the extension member when the latter reaches its horizontal position, a bolster member disposed transversely of the rear of the bedding support of the main frame and connected thereto at its upper edge by a flexible joint, and means carried by the main frame and actuated by the forward sliding movement of the bedding support of the main frame automatically to raise the bolster to an inclined position.

3. An article of furniture for use as a chair

or bed, comprising, a main frame including hollow side boxes having arcuate slots in their inner side walls, an upright back board connecting said side boxes, and a movable bedding support extending between the side boxes; elevating means for the said bedding support, said elevating means including pins slidably carrying the bedding support and movable in said arcuate slots, hinge bars pivotally connected to the side boxes and operatively connected to said pins; an extension including side arms, a seat, and a back rest, the latter normally engaging said upright back board, a second bedding support carried by the underside of the extension, said extension pivotally connected at its front end to the said hinge bars above their point of pivotal connection with said side boxes and having means to engage and move the hinge bars when the extension is tilted forwardly relative to the main frame to expose said second bedding support, said hinge bars, when moved by the extension, actuating said pins to effect the elevation and forward sliding of the movable bedding support of the main frame to align said support with the bedding support of the extension.

4. An article of furniture according to claim 3, wherein the bedding support of the main frame has side frame members provided with longitudinal slots which, when said bedding support is at rest in the main frame, lie rearwardly of the upper ends of the arcuate slots in the side boxes, whereby, when said bedding support is elevated, said pins will move to the forward extremities of the slots and slide the bedding support forward.

5. An article of furniture according to claim 3, wherein, the back rest has a releasable latch engagement with the upright back board of the main frame.

6. An article of furniture according to claim 3, wherein, the side arms of the extension are hollow and a rod passes transversely through the side arms and back rest to hold the back rest in place when the extension is tilted forwardly, and link means in the hollow side arms for connecting the ends of said rod with the upper end of each hinge bar.

7. An article of furniture according to claim 3, wherein, the elevating means for the bedding support of the main frame includes triangular rocker members having their apices engaging said pins, link members connecting corresponding base corners of each pair of rocker members, and pivots connecting the other base corners of the rocker members with the inner faces of the hollow side boxes at a point coaxially with the radius of said arcuate slots, and links connecting the pin of each front rocker with the lower ends of the related hinge bars.

8. An article of furniture according to claim 3, wherein, each of the side arms of the extension is provided with a socket, and each of the hinge bars is provided with a locking bar slidably guided relative to the hinge bar, a lateral pin on each locking bar, brackets carried by the inner walls of the hollow side boxes of the main frame and having slots for receiving and guiding the lateral pins of the locking bars, whereby when the hinge bar is tilted forwardly by the movement of the extension section, the said locking bars will be moved forwardly to engage its related socket in one of the side arms.
